William W. Meekins

UNITED STATES PATENT OFFICE.

AUGUSTUS R. MORGAN, OF FARIBAULT, MINNESOTA.

AIR-VALVE PROTECTOR FOR RADIATORS.

1,326,768.

Specification of Letters Patent. Patented Dec. 30, 1919.

Application filed March 26, 1919. Serial No. 285,266.

To all whom it may concern:

Be it known that I, AUGUSTUS R. MORGAN, a citizen of the United States, residing at Faribault, in the county of Rice and State 5 of Minnesota, have invented certain new and useful Improvements in Air-Valve Protectors for Radiators; and I do hereby declare the following to be a full, clear, and exact description of the invention, such as

10 will enable others skilled in the art to which it appertains to make and use the same.

My invention has for its object to provide a simple, cheap and highly efficient protecting case for the air valves of radiators; and to such ends, generally stated, the 15 invention consists of the novel construction and combination of parts hereinafter described and defined in the claims.

The protecting case comprises two parts, 20 to wit, back plate and inclosing shell, and this back plate and shell have interlocking parts that are adapted to be interlocked and disengaged quite readily by a person knowing the manner of manipulation, but which 25 cannot be disengaged by any ordinary person not knowing the proper manner of manipulation for effecting such result.

The invention is illustrated in the accompanying drawings wherein like characters 30 indicate like parts throughout the several views. Referring to the drawings,

Figure 1 is a perspective view with some parts broken away, showing the case applied around the air valve of a radiator, one 35 of the radiator sections being shown in part;

Fig. 2 is a face view of the so-called back plate; and

Fig. 3 is a face view of that part of the 40 shell that is engageable with the back plate.

Fig. 3^a is a fragmentary view taken on the line 3^a—3^a of Fig. 3.

A radiator section is indicated by the 45 numeral 4 and its air valve by the numeral 5.

The back plate of the casing is indicated by the numeral 6 and the inclosing shell by the numeral 7. The back plate 6 is provided with a perforation through which is passed the threaded stem 5^a of the valve.

50 This threaded stem 5^a, as is well known, is tapped into the radiator section. To further hold the back plate 6 secured to the ra-

diator section 4, a screw 8 is applied therethrough and screwed into the radiator section. In the arrangement illustrated, the 55 valve 5 is extended upward from its stem 5^a, and hence, the screw 8 is located above the stem 5^a; but in a reverse arrangement, that is, where the valve 5 is extended downward from its stem 5^a, the screw 8 would be located below the stem 5^a.

At the transverse central portion of its top, the back plate 6 is formed with a spring tongue or central portion 9, the free upper end of which is outwardly bent to form a 65 cam surface at 9^a and just below this cam surface, the tongue 9 has a lock slot or perforation 9^b. Near its lower portion and at each side, the back plate 6 is provided with vertical slots 10 which, at their upper extremities, have inwardly extended notches 10^a, and at their outer extremities have outwardly extended notches 10^b. The shell 7, at the upper extremity of its inner face, is provided with a down turned flange 11 75 which, at its transverse central portion has an inturned lock lug or extension 11^a. At its inner edges, near its lower end, the sides of the shell 7 are formed with inturned lock lugs or projections 12.

The operation of interlocking the shell 7 to the case 6 is as follows:

The lock lug 11^a is placed on the inner surface of the bevel portion 9^a of the tongue 9 and the lower portions of the sides of the 85 shell 7 are pressed together so as to bring the lock lugs 12 into alinement with the notches 10^a, and the side portions of said lugs into alinement with the slots 10. Then the said lugs 12 are pressed backward 90 through the notches 10^a and then the entire shell is slid downward until the lug 11^a is sprung into interlocking engagement with the notch 9^b of the spring tongue 9 and this will carry the lugs 12 down into alinement with the notches 10^b. Then when the said inclosing shell is released, its side will spring apart and the stems of the lugs 12 will be carried into the notches 10^b. When the shell is thus interlocked to the base plate it 100 will be held against vertical releasing movement, first by the engagement of the lug 11^a with the notch 9^b and, second, by the engagement of the lugs 12 with the notches

10^b. The shell can be released only by first springing the tongue 9 so as to carry the notch 9^b thereof out of engagement with the lug 11^a, and then while the said notch 5 is held disengaged from said lug, the sides of the lower portions of the shell 7 must be pressed inward and then the shell can be forced upward and disengaged from the back plate. However, the tongue 9 cannot 10 be disengaged from the lug 11 by the fingers but only by a properly constructed tool which must be designed so that it can be inserted between the radiator section and the back of the tongue 9, and then turned or 15 otherwise manipulated so as to spring the tongue 9 outward. With a properly constructed tool, a person knowing the proper manner of manipulation, can easily remove the shell, but the removal of the shell by 20 a person not having the proper tool or understanding the operation, would be practically impossible.

The shell 7, in its top, is preferably provided with one or more vent holes 13. 25 The device described may be made at small cost and very easily and quickly applied to the air valves of radiators. It may be made either plain or ornamental in appearance, so that it will add, rather than 30 detract from the design of the radiator, and when applied, effectually prevents undesired manipulation of the air valve. In practice, it has been found that where the air valve is exposed, persons will frequently open the 35 valve to permit the escape of air and then leave the same open for the desired escape of steam or water. Moreover, it frequently happens that these air valves are removed and stolen, and this, of course, will be prevented by the application of the protecting case. 40

As is well known, to remove the air valve requires rotation thereof on the axis of its stem 5^a, and, of course, when the case is 45 applied, the said valve cannot be thus rotated, first because it cannot be reached, and second, because it cannot rotate within the shell. The shell, of course, is held against rotation on the axis of the stem 5^a by the 50 screw 8, and this screw cannot be reached

or removed as long as the shell is interlocked to the back plate.

What I claim is:

1. A protecting casing for radiator air valves comprising a back plate and a shell, 55 the said back plate and shell having interlocking parts capable of being engaged and disengaged by manipulation in a predetermined manner, and devices within the shell for securing the back plate to a radiator, and which latter devices are covered and protected by said shell so that they cannot be reached or manipulated while the shell is in working position. 60

2. A protecting casing for radiator air valves, comprising a back plate and a shell, said back plate having a spring tongue and laterally spaced vertical slots, said tongue having a lock notch and said slots having inwardly extended notches at their upper 65 extremities and outwardly extended notches at their lower extremities, said shell having an upper end flange with an inturned lock lug for interlocking engagement with the notch of said spring tongue, and the said shell, at the lower portions of its sides, having inturned lock lugs insertible into the upper end notches of said slots and slideable downward through said slots into interlocking engagement with the lower notches of 70 said slots. 75

3. The combination with a radiator and an air valve, the latter having a threaded stem tapped into said radiator section, of a valve inclosing casing comprising a back 85 plate and a shell, said back plate being clamped to said radiator section by the stem of said valve and having a screw further securing the same to the radiator section, and the said back plate and shell having 90 interlocking parts adapted to be interlocked and disconnected by manipulation in a predetermined manner.

In testimony whereof I affix my signature in presence of two witnesses.

AUGUSTUS R. MORGAN.
